US0D1070857S

(12) **United States Design Patent** (10) Patent No.: **US D1,070,857 S**
(45) Date of Patent: ** Apr. 15, 2025

(54) **GAMING MONITOR**

(71) Applicant: **LG ELECTRONICS INC.**, Seoul (KR)

(72) Inventors: **Yongsoo Kim**, Seoul (KR); **Yeonjin Kim**, Seoul (KR); **Daihyung Ryu**, Seoul (KR); **Heeju Chang**, Seoul (KR); **Daesung Lee**, Seoul (KR)

(73) Assignee: **LG ELECTRONICS INC.**, Seoul (KR)

(**) Term: **15 Years**

(21) Appl. No.: **35/520,403**

(22) Filed: **Feb. 22, 2024**

(80) **Hague Agreement Data**

Int. Filing Date: **Feb. 22, 2024**

Int. Reg. No.: **DM/235746**

Int. Reg. Date: **Feb. 22, 2024**

Int. Reg. Pub. Date: **Mar. 22, 2024**

(30) **Foreign Application Priority Data**

Sep. 14, 2023 (KR) 30-2023-0036350

(51) LOC (15) Cl. **14-03**

(52) U.S. Cl.

USPC **D14/375**

(58) **Field of Classification Search**

USPC D14/125, 126, 127, 133, 336, 341, 371, D14/373, 374, 375, 376, 377, 378, 379, D14/380, 381, 382

CPC G06F 1/1601; G06F 1/1605; G06F 1/162; H04N 5/64
